UNITED STATES PATENT OFFICE.

OSCAR WERNER NILSON, OF MIDDLETOWN, AND FRANK ALOISIOUS BRASSILL, OF HARTFORD, CONNECTICUT, ASSIGNEES TO MIDDLESEX MACHINE WORKS, OF MIDDLETOWN, CONNECTICUT, A COPARTNERSHIP COMPOSED OF OSCAR W. NILSON, OF MIDDLETOWN, CONNECTICUT, AND FRANK A. BRASSILL, OF HARTFORD, CONNECTICUT.

GRINDING-MACHINE.

1,266,848.

Specification of Letters Patent. Patented May 21, 1918.

Application filed March 6, 1917. Serial No. 152,709.

To all whom it may concern:

Be it known that we, OSCAR WERNER NILSON, a citizen of the United States, residing at Middletown, in the county of Middlesex and State of Connecticut, and FRANK ALOISIOUS BRASSILL, a citizen of the United States, residing at Hartford, in the county of Hartford and State of Connecticut, have invented certain new and useful Improvements in Grinding-Machines, of which the following is a specification.

Our invention relates to improvements in grinding machines, and the object of our improvement is simplicity and economy in construction and convenience and efficiency in use.

In the accompanying drawing:—

Figure 1 is a front elevation of our improved grinding machine.

Fig. 2 is a similar view of the supporting column and head, the bed-plate being turned 90 degrees on the column from the position shown in Fig. 1.

Fig. 3 is a front elevation of the column. Fig. 4 is a fragmentary front elevation on an enlarged scale of a part of the column and adjacent parts.

Fig. 5 is a sectional view on the line $\alpha-\alpha$ of Fig. 4.

Our improved grinding machine comprises a vertical column or standard 10 supported by a base 11 and surmounted by a fixed head 12 and a bed-plate structure 13 supported from the said column 10 in a special manner to be described.

The head 12 is secured on the upper end of the column 10 by bolts 14 and comprises a pair of bearings 15 in spaced relation supporting a shaft 16 on which is mounted a driving pulley 17 between the bearings 15 and having ends overhanging the said bearings 15 for receiving the grinding wheels 18.

The bed-plate structure 13 comprises the upper plate 19 that serves as the bed-plate proper on which the work is secured in the usual manner, either directly or by means of centers or a magnetic chuck, not shown, and which features do not pertain to the present invention.

The upper plate 19 is slidably supported

on an intermediate plate 20 and is moved longitudinally back and forth thereon by means of a rack and pinion feed operated by the hand wheel 21.

The intermediate plate 20 is slidably supported on the upper horizontal face 22 of an angle-bed 23, suitably to provide a transverse feed by means of a screw operated by the transverse feed hand wheel 24.

The angle-bed 23 comprises the horizontal face 22 on the upper end and a vertical operating face 25 at one side suitably channeled to slidably engage with the dovetailed guide rib 26 that constitutes the body portion of the vertical main supporting plate 27.

A vertical feed for the angle-bed 23 is provided by means of a screw 29 provided with a set of bevel gears 30 and operated by the hand wheel 31, which as shown is mounted on a stub shaft 32 and is directed at an angle of about 45 degrees to the plane of the vertical plate 27. The shaft 32 is supported by a bearing 33 in one of the webs 34 that form the side walls of the angle-bed 23.

The vertical, main supporting plate 27 is supported from a pair of trunnions 28 provided on the column 10 and in spaced relation, by means of a split bearing composed of a plate member 41 secured to the plate 27 and a cap member 35 that serves to complete the bearings.

The column 10 is a cylindrical structure of substantial dimensions, and is reduced appreciably to provide two similar annular recesses that constitute the trunnions 28.

The plate member 41 of the split bearing comprises in each case on the inner side a semi-annular bearing portion 36 that fits in the trunnion 28 and on the outer side has a pair of tangential arms 37 that combine to form a transverse support for the main supporting plate 27 being secured to the rear face of the said main supporting plate 27 by screws or bolts 40.

The cap member 35 is of semi-annular form, suitable to complete the annular form of the slit bearing as mentioned, and is secured to the bearing portion 36 of the plate member 41 by a plurality of screws 38, the 100

complete split bearing being of suitable dimensions to fit into and substantially fill the bearing recess 28.

5 The cap member 35 is provided with a locking screw 39.

As described we have provided in our improved grinding machine a double bearing structure for the main supporting plate 27 that supports the angle bed 23, whereby 10 the said supporting plate and the bed plate structure supported thereby can be swung completely around the column 10 and may be locked in any desired position by means of the locking screw 39.

15 When thus locked therein provision is made for vertical, transverse, and longitudinal feeds for the bed plate and work supported thereto, and the structure is such that accuracy of the feed in the vertical direction as well as the transverse and the longitudinal is insured.

20 Accordingly, as described, the structure is adapted for accuracy in grinding for either surface or cylindrical grinding.

25 The double bearing as shown provides two coöperating thrust bearings for positioning the moving structure longitudinally relatively to the column or standard as well as 30 providing a double bearing for rotative movement.

It is to be noted that the two separate 35 trunnions 28 are provided in a unitary, integral column or standard structure by recessing as described, there being no separate or loose pieces to hold the split bearings in position.

We claim as our invention:—

1. A grinding machine comprising a cy-

lindrical supporting column extending upwardly from a base, a spindle supporting 40 head on the upper end of the said column, a pair of trunnions on the said column in spaced relation, bearings engaged with the said trunnions, and a bed-plate structure supported by the said bearings, the said 45 trunnions being in the form of reduced portions of the said column, and the said bearings being in the form of split-bearings, fitting in the said reduced portions.

2. A grinding machine comprising a supporting column, a bed-plate structure supported from the said column, the means of support for the said structure from the said column comprising a pair of bearings in spaced relation, and the said column being 55 reduced to provide a pair of bearing recesses to fit and to operatively receive the said bearings.

3. In a grinding machine, a column having a base at the lower end and means for receiving a head at the upper end, the body portion of the said column being of cylindrical form and having a pair of annular recesses in the periphery in spaced relation 60 suitably to receive bearing structures for supporting a bed-plate structure and each of the said annular recesses comprising a pair of radial end wall surfaces suitable for serving as thrust bearings and a cylindrical bearing portion connecting the said end wall 65 surfaces.

OSCAR WERNER NILSON.
